UNITED STATES PATENT OFFICE.

SEYMOUR LANDON ALVORD, OF WINSTED, CONNECTICUT.

KNIFE-BLADE LEATHER-PUNCH.

No. 833,146.

Specification of Letters Patent.

Patented Oct. 16, 1906.

Application filed April 6, 1906. Serial No. 310,294.

To all whom it may concern:

Be it known that I, SEYMOUR LANDON ALVORD, a citizen of the United States of America, residing at Winsted, in the county of 5 Litchfield and State of Connecticut, have invented certain new and useful Improvements in Knife-Blade Leather-Punches, of which the following is a specification.

The object of the invention is to provide a 10 device of the class specified having features of novelty and advantage.

Figure 1 is a front view of a blade embodying my invention. Fig. 2 is an edge view thereof. Fig. 3 is a sectional view on the line 15 3 3 of Fig. 2. Fig. 4 is a view of the back of the blade. Fig. 5 is a view of a knife with the blade closed into the handle.

Referring to the drawings, the blade is shown in general at *a*, having a substantially 20 flat face *b* and curved rear side *c* and a flat rounded point *d*. The blade is provided with a longitudinal cutting edge *e*, which is raised slightly above the plane of the flat face 25 of the blade. The rounded point is preferably sharpened on its front and back edges.

By following out my invention it is possible to forge the blade, and the shape of the blade is such that it can be ground and finished on its front and rear sides. By providing a blade with the flat rounded sharpened point it begins to cut as soon as it is applied to the leather or whatever material it is to be used on and can be forced through the leather or other material with very slight exertion.

30 The blade closes into the knife-handle exactly as the regular knife-blades, the sharpened point and cutting edge being protected and the blade when closed into the knife presenting the appearance of the ordinary blade.

I claim as my invention—

1. An article of the character described comprising a blade having a substantially flat face, a curved rear side, a longitudinal cutting edge upstanding slightly above the plane of the flat face and a rounded and sharpened end. 40 45

2. An article of the character described comprising the blade having a substantially flat face, a curved rear side, a longitudinal cutting edge upstanding slightly above the plane of the flat face, and a double-edged end, substantially as described. 50

3. The combination with a pocket-knife handle, of a leather-punch blade pivoted thereto, said blade having a flat face and curved rear side, a double-edged end, and a cutting-flange starting at the point and in the plane of the flat face of said blade and extending along the inner edge of and toward the base of said blade and upstanding above the flat face thereof and gradually increasing in height from the flat point to the base. 55 60

4. An article of the character described comprising a blade having a substantially flat face curved rear side and a cutting edge starting at the haft and extending along the inner side of said blade and around the rounded end thereof, said cutting edge being upturned along the inner edge of the blade to form a cutting-flange which stands above the plane of the flat face of the blade, substantially as described and for the purposes set forth. 65 70

In testimony whereof I affix my signature in presence of two witnesses.

SEYMOUR LANDON ALVORD.
